DOUBLE HUNG WINDOW SASH AND FRAME CONSTRUCTION

Original Filed Nov. 29, 1933

UNITED STATES PATENT OFFICE

2,084,620

DOUBLE HUNG WINDOW SASH AND FRAME
CONSTRUCTION

Edwin Moll, Portland, Oreg.

Refiled for abandoned application Serial No.
700,229, November 29, 1933. This application
August 12, 1936, Serial No. 95,642

2 Claims. (Cl. 16—197)

My present application which is a refile of my abandoned application Ser. No. 700,229 filed Nov. 29/33 relates to my United States patent application upon Double hung window sash and frame construction, as evidenced by Serial No. 633,986, filed in the U. S. Patent Office under date of Sept. 20, 1932, and which was issued as Patent No. 2,007,979, July 16, 1935.

My present invention provides adjustable means for loading the spring supports to compensate for the difference in weight of different window sashes to be hung within the window frame, the spring supports being disposed within each side of the window frame. The difference 15 in the weight of glass used within the window sash and the materials from which the sash is made very often varies substantially.

In my new and improved construction, as evidenced by this application, I provide means 20 for accommodating the weight to the springs without the necessity of cutting the same.

A still further object of my invention is to provide means for positioning and supporting the sash pulley within the post of the window frame.

25 A still further object of my present invention consists in providing hardware that is adapted for placement within the post and that may be adjusted for automatically supporting the window sashes in placed position without overloading the spring support or without the cutting of the spring support to meet the purposes intended.

A still further object of this invention consists in so constructing and assembling the device that it may be placed in position upon the posts of 35 the window frame before the posts have been assembled into the completed frame.

With these and incidental objects in view, the invention consists in certain novel features of construction and combination of parts, the essential elements of which are set forth in the appended claims, and a preferred form of embodiment of which is hereinafter shown with reference to the drawing which accompanies and forms a part of this specification.

45 In the drawing:

Fig. 1 is a fragmentary sectional side view of the outside of the window frame.

Fig. 2 is a sectional side view of the mechanism illustrated in Fig. 1. This view is taken on line 50 2—2 of Fig. 1, looking in the direction indicated.

Fig. 3 is a fragmentary, rear side view of the assembly. This is an enlarged view and is made particularly to illustrate the means for attaching the spring support in adjusted placement.

55 Fig. 4 is a side view of the inside of the window frame post illustrating a pulley residing recess as having been cut out of the inside of the post to provide a place therein for supporting the pulley assembly.

Fig. 5 is a sectional end view of the mechanism 5 illustrated in Fig. 3. This view is taken on line 5—5 of Fig. 3, looking in the direction indicated.

Fig. 6 is a sectional end view of the post of the window frame.

Like reference characters refer to like parts 10 throughout the several views.

The post of the window frame is designated as 1. In my present construction I rout out a recess 2 within the side wall of the post of the window frame. A slit 3 is cut within the post 15 and the same extends longitudinally and centrally of the post and to the extreme ends 4 and 5 of the routed recess 2.

I secure a guide rod 6 within the inside of the post by any suitable fastening means as through 20 the use of screws 7 and 8 that are disposed at the ends of the guide rod 6. This guide rod is preferably made of tubular or round material, the purpose and object of which is to form a supporting means and guide for the fastening 25 plate 9. The fastening plate 9 has a serrated or toothed edge 10.

Fastening ears 11 and 12 are disposed at the oppositely disposed ends of the fastening plate 9 and the guide rod 6 passes through these ears 30 and permits the fastening plate to slide freely along the guideway 6. A plurality of pairs of spaced slits 13 and 13A are disposed within the plate 9. A bracket 14 is adjustably secured to the plate 9, the bracket having supporting legs 35 15 and 16 extending from one edge thereof and being adapted to be passed through one of the pairs of spaced slits 13 and 13A. The leg 16 extends through the slits 13 and the leg 15 extends through the slit 13A and as the legs 16 40 and 15 are passed through the slits 13A and 13 respectively and the bracket 14 is moved longitudinally of the slits, the foot 17 engages the face 19 of the plate 9 and locks the same in place- 45 ment. The inner edge 20 of the foot 17 is pref- erably inclined at an angle to that of the edge 18 of the bracket body so that a tight frictional engagement is developed between the foot 17 and the face 19 of the plate 9 when the bracket is forced home within the slits.

An ear 21 upwardly extends from the outer edge of the bracket 14 to form a hook on which the window sash pulley 22 may be hung. The sash cord 23 is trained about the pulley and the end of the sash cord is fastened to the bottom 55

of the respective window sashes, not here shown.

A reacting element as a coil spring 24 is secured upon its one end to the window frame by any suitable support, as through the use of a screw eye 25. The screw eye 25 is preferably secured to the top cross member 26 of the window frame and the oppositely disposed end of the reacting element 24 is secured to an adjustable hook 27. The adjustable hook 27 is hinged 10 secured to a strip member 28 by any suitable hinge pin 29 and a locking member 30 carried by the adjustable hook 27 is adapted to be hinged into and out of locking engagement with the teeth 10 of the plate.

15 The strip member 28 is secured to the plate 9 by return bends 31 and 32 that are formed in the strip member 28 and that engage the outer face edges 35 of the plate 9 to form a guideway in which the rod 6 is disposed.

20 Upon installation of the window frame in place in the wall opening prepared for it, the sashes are fitted and hung, and the spring 24 is adjusted to the desired tension by manipulation of the locking latch 27 relative to the fastening plate 9, 25 to which in turn pulleys 22 are suspended by means of the brackets 14. When the desired spring tension is secured, the window frame casing is placed in position. Subsequent adjustment of the spring tension may be effected directly by first removing the side casing members.

30 In operation, the opposite ends of the sash cord 23 are secured to the bottom ends of the respective sashes. The tension of the spring is set so that it is sufficient to hold the sash in any 35 position but is insufficient to overcome the friction between the sash and the frame to raise the sash without added force being applied to the sash. When the bottom sash is raised, tension upon the spring 24 will be relieved and the plate 9 will move on the rod 6 toward the top.

40 If the top sash is lowered, a greater tension will be placed on the spring 24 by the movement of the plate 9 downwardly on the rod 6.

45 If the bottom sash is raised and the top sash is lowered an equal amount, the tension on the

spring will be unchanged as there would be no movement of the plate 9 either up or down.

While the form of mechanism herein shown and described is admirably adapted to fulfill the objects primarily stated, it is to be understood 5 that it is not intended to confine the invention to the embodiment herein shown and described, as it is susceptible of embodiment in various forms, all coming within the scope of the claims which follow.

10 What I claim is:

1. A sash balance for association with the post of a window frame having a pulley receiving recess in one side of the post and a slit extending through the wall and longitudinally of the post 15 and recess, said sash balance comprising a guide secured at its ends to the post, a slide movable relative to the guide, said slide having pairs of spaced slits therein and a toothed edge, a bracket adjustably secured within the spaced slits, a sash 20 cord pulley removably attached to the bracket, a hook cooperating with the toothed edge of the slide to adjustably secure the hook on said slide, and a reacting element, one end of which is secured to said hook, the other end being adapted 25 to be secured to the window frame.

2. A sash balance for association with the post of a window frame having a pulley receiving recess in one side of the post and a slit extending through the wall and longitudinally of the post 30 and recess, said sash balance comprising a guide secured at its ends to and spaced from the post, a plate member disposed upon the guide and slideable relative thereto, said slideable plate having pairs of spaced slits therein and a toothed edge, 35 a bracket that may be secured in any of the pairs of slits, a sash cord pulley removably attached to the bracket, a hook slidably secured to the slideable plate, a locking lug disposed upon the hook and adapted to cooperate with the toothed 40 edge of the slideable plate to adjustably position the hook relative to the slideable plate, and a reacting element, one end of which is secured to said hook, the other end being secured to the top member of the window frame.

45 EDWIN MOLL.
